DESIGN FOR A SET OF PICTURE GAME PIECES

George Mysels, New York, N. Y.

Application June 18, 1945, Serial No. 120,193

Term of patent 14 years

(Cl. D34—5)

To all whom it may concern:

Be it known that I, George Mysels, a citizen of the United States of America and residing at New York city, in the county and State of New York, have invented a new, original, and ornamental Design for a Set of Picture Game Pieces, of which the following is a specification, reference being had to the accompanying drawing, forming a part thereof.

Fig. 1 is a plan view of the obverse side of a set of picture game pieces, showing my new design.

Fig. 2 is a plan view of the reverse side thereof.

Fig. 3 is a side view of the set of picture game pieces shown in Figs. 1 and 2.

I claim:

The ornamental design for a set of picture game pieces, substantially as shown.

GEORGE MYSELS.
